United States Patent Office

Des. 229,156
Patented Nov. 13, 1973

229,156

HOLDER FOR A BEVERAGE CAN

Robert A. Moussette, 4572 Via Marina, Apt. 103,
Marina del Rey, Calif. 90291

Filed Mar. 30, 1972, Ser. No. 239,857

Term of patent 14 years

Int. Cl. D7—01

U.S. Cl. D7—70

FIG. 1 is a top front perspective view of a holder for a beverage can showing my new design with the cover in an open position;

FIG. 2 is a rear elevational view thereof; and

FIG. 3 is an elevational view thereof as seen from the left of FIG. 2.

The bottom of the design is substantially plain and unornamented.

I claim:

The ornamental design for a holder for a beverage can, as shown and described.
